[57] CLAIM

The ornamental design for a respirator mask, as shown and described.

DESCRIPTION

FIG. 1 is a front perspective view of a respirator mask showing my new design;
FIG. 2 is an enlarged side elevational view thereof, the opposite side being a mirror image;
FIG. 3 is an enlarged top plan view thereof;
FIG. 4 is an enlarged front elevational view thereof;
FIG. 5 is an enlarged bottom plan view thereof;
FIG. 6 is an enlarged back elevational view thereof;
FIG. 7 is a front perspective view of a second embodiment thereof, showing an alternate filter cartridge; and,
FIG. 8 is a front perspective view of a third embodiment thereof, showing an alternative clip-on filter cartridge.
The respirator mask for the second and third embodiments (FIGS. 7 and 8) is the same as the first embodiment, the only difference being in the filter cartridges.
The person shown in broken lines in FIGS. 1, 7 and 8 is shown for illustrative purposes only and forms no part of the claimed design. The cross hatch shading in FIGS. 1, 2, 4 and 8 is understood to repeat throughout the filter.
